UNITED STATES PATENT OFFICE

CHAUNCEY F. SHULTZ, OF ST. LOUIS, MISSOURI

BRUSH-MAKING MACHINE

Application filed January 31, 1930. Serial No. 424,753.

My invention relates to a machine for making brushes and particularly to the type of machine in which radial wires, bristles or fibers are twisted between two or more central or core strands of relatively heavy wire to produce a brush of cylindrical form. Heretofore it has been necessary to trim the ends of the radial strands, after the formation of the brush, to bring the brush into proper cylindrical form. This is due to the fact that during the twisting operation some or all of the strands become more or less displaced in the direction of their length so that their ends do not project equal distances at each side of the core. Further, it has been difficult to maintain a uniform distribution of the strands in the direction of the length of the brush.

The object of my invention is to provide guiding means engaging the ends of the cross strands of the brush during the twisting operation thus insuring the formation of a truly cylindrical brush and at the same time securing uniform distribution of the strands in a longitudinal direction.

In the accompanying drawings, which illustrate one form of machine made in accordance with my invention, Figure 1 is a side elevation on a reduced scale; Figure 2 is an end view of the guide; Figure 3 is a cross section of the guide showing the core and cross strands in position; and Figure 4 is a view showing means for reducing the internal diameter of the guide.

The machine comprises a head stock 5 and a tail stock 6 carried on a bed plate 7. Mounted in the head stock is a rotary spindle 8 driven from a pulley 9 and carrying the rotating chuck 10 for engaging one end of the core wires 11. The other ends of the core wires are engaged by a non-rotating chuck 12 carried by a rack bar 13 sliding in the tail stock. During the formation of a brush the chuck 12 travels toward the chuck 10 due to the shortening of the core resulting from the twisting of the wires composing it. In order to maintain the necessary tension on the core the longitudinal movement of the chuck 12 is retarded by a band brake 14. The above mentioned parts are

in common use and form no part of my invention except in combination with the guiding means hereinafter described.

Vertically adjustable in the bed plate by means of a set screw 15 is a post 16 on which is mounted a block 17 provided with ways 18 in which slides a plate 19 forming the base of the guide. The guide which is cylindrical in form is composed of a lower part 20 and an upper part 21 pivotally secured together by a hinge joint 22. The dividing line between the two parts is somewhat above the axial line of the cylinder for the purpose hereinafter set forth. The end of the guide adjacent to the non-rotating chuck 12 is closed by a divided end plate 23 having a central opening 24 for the passage of the core wires. A handle 25 is provided for swinging the upper part of the guide on its hinge joint 22.

The operation of the machine is as follows: The guide is positioned as shown in Figure 1, concentric with the core wires and close to the chuck 12. The upper part of the guide is swung back on its hinge leaving the lower part open at the top. The cross or filler wires 27 are now inserted in vertical position between the core wires, their lower ends resting on the bottom of the lower part of the guide. In case only two core wires are used, the guide is now closed and the twisting operation performed. When, however, four core wires are used, as shown in the drawings, the core is rotated one quarter of a revolution to bring the first set of filler wires into horizontal position, and a second set inserted in the same manner as the first and at right angles thereto. It will be understood that the chuck 12 is capable of 90 degree play with respect to the rack bar to permit of such movement of the core. This, however, in no way interferes with its function of holding the core against rotation during the twisting operation. It is to provide retaining walls for both ends of the first set of filler wires while the second set is being positioned that the guide is divided above the middle. In case the machine is to be used only for brushes with a single set of filler wires, the guide may be centrally divided.

After both sets of filler wires are in place the guide is closed and the twisting operation performed in the usual manner. As the chuck 12 moves toward the chuck 10, due to the shortening of the wires, it strikes the end plate 23 and slides the guide before it on its ways. This is essential, however, only when the interior diameter of the guide is less than the exterior diameter of the chuck. Otherwise the guide may be stationary instead of sliding, the end wall being omitted so that the chuck may enter the guide.

When a different size of brush is to be made, a guide of a different size may be substituted, being centered by the vertical adjustment of the post 16. Or, one guide may be used of several sizes of brush by the use of removable fillers 26, as shown in Figure 4.

The use of the guide holds the filler wires perfectly symmetrical with respect to the core so that no trimming of the brush is necessary. I find also that the friction of the ends of the filler against the walls of the guide keeps these wires evenly distributed, preventing bunching with resultant lack of evenness in the completed brush.

Having fully described my invention, what I claim as new and desire to secure by Letters Patent of the United States is:

30 1. In a device of the class described, the combination with core twisting means, of a hollow cylindrical guide surrounding the core and holding the fillers in symmetrical relation to the core during the twisting operation.

35 2. In a device of the class described, the combination with core twisting means, of a longitudinally travelling hollow cylindrical guide surrounding the core and holding the fillers in symmetrical relation to the core during the twisting operation.

40 3. In a device of the class described, the combination with core twisting means, of a hollow cylindrical guide surrounding the core and holding the fillers in symmetrical relation to the core during the twisting operation, said guide being divided to permit of the insertion of the fillers.

45 4. In a device of the class described, the combination with core twisting means, of a hollow cylindrical guide surrounding the core and holding the fillers in symmetrical relation to the core during the twisting operation, said guide being divided along a line above the axis to permit of the insertion of fillers in a vertical direction and to form retaining walls for both ends of horizontal fillers.

50 5. In a device of the class described, the combination with core twisting means comprising a head stock and a tail stock having relative movement toward and away from each other, of a hollow cylindrical guide surrounding the core and holding the fillers

in symmetrical relation to the core during the twisting operation.

In testimony whereof, I hereunto affix my signature, this 28th day of January, 1930.

CHAUNCEY F. SHULTZ.
